UNITED STATES PATENT OFFICE.

THOMAS B. WINNETT, OF LOS ANGELES, CALIFORNIA.

REENFORCED COLLAR.

Application filed October 20, 1921. Serial No. 509,035.

To all whom it may concern:

Be it known that I, THOMAS B. WINNETT, a citizen of the United States, residing at Los Angeles, in the county of Los Angeles and State of California, have invented new and useful Improvements in Reenforced Collars, of which the following is a specification.

My invention relates to a reenforced collar, the principal object of my invention being to provide men's and boys' linen collars with reenforcing elements, preferably sections of fabric, and which latter are preferably located between the sections of material that are utilized in the construction of the collar, and said reenforcing means being located at the points that are subject to the greatest wear and strains while the collar is being laundered, thus materially increasing the life or period of service of the collar and at the same time providing a construction that will tend to cause the collar to retain its shape while being worn.

Further objects of my invention are to provide a reenforced collar that may be easily and cheaply produced, and which will be effective in materially reducing the tendency of the collar to break along the lines where it is folded.

With the foregoing and other objects in view, my invention consists in certain novel features of construction and arrangement of parts that will be hereinafter more fully described and claimed and illustrated in the accompanying drawings, in which:

Figure 1 is an elevational view of a section of material in tape form, and which may be utilized as a reenforcing member for collars of my improved construction.

Fig. 2 is a perspective view of a section of the reenforcing material bent to proper shape for insertion in the end portion of a collar.

Fig. 3 is a perspective view of a portion of a collar that is reenforced in accordance with my invention.

Fig. 4 is an enlarged horizontal section taken approximately on the line 4—4 of Fig. 3.

Fig. 5 is a perspective view of a collar having its folded over upper edge reenforced in accordance with my invention.

In producing reenforced collars of my improved construction, a relatively narrow

strip of flexible material, preferably closely woven fabric, is inserted between the outer and inner sections 11 and 12 of material that form the body of the collar, and said strip of reenforcing material is preferably arranged immediately adjacent to the edges at the ends of the collar, or those portions that are brought together at the front of the neck band of the shirt.

This reenforcing section of material may be secured to the sections 11 and 12 of material that form the body of the collar in any suitable manner, but I prefer to arrange one edge of the reenforcing strip between the inturned edges of the fabric sections 11 and 12, and secure said inturned edges to the edge of the reenforcing strip by one or more rows of stitches, and which arrangement firmly secures the reenforcing element in position within the body of the collar.

The inner portion of the reenforcing strip extends downwardly between the sections of material forming the inner band of the body of the collar, and the buttonhole 13 that is formed through the inner portion of said collar is also formed through the end portion of the section of reenforcing material. Thus when the section of material 10 is properly positioned in the end portion of the body of a collar, it reenforces the edge of the body of the collar at said inner end, and also reenforces the front buttonhole, and likewise reenforces that portion of the body of the collar that is folded over to form the inner and outer folds or sections of the collar.

In some instances it may be found desirable to extend a relatively narrow section of reenforcing material the entire length of the collar and along the line where the same is folded, such construction being illustrated in Fig. 5. Where such provision is made, the collar is reenforced against breaking along the line of this fold, and as a result the life or term of service of the collar is prolonged.

Thus it will be seen that I have provided a reinforced collar that is of relatively simple structure, capable of being easily and cheaply produced, and very effective in performing its intended functions.

It will be understood that minor changes in size, form and construction of the various parts of my improved reinforced collar may be made and substituted for those herein

shown and described without departing from the spirit of my invention, the scope of which is set forth in the appended claims.

I claim as my invention:

- 5 1. A reenforced collar comprising outer and inner sections having their edges folded inwardly at their ends and a reenforcing strip placed between the inwardly folded edges and reaching from one edge of the collar to the other edge across the end.
- 10 2. A reenforced collar comprising an outer section and an inner section, reenforcing strips inserted between the sections at their ends and extending from one side edge to the other side edge, and a reenforcing strip inserted between the outer and inner sections substantially half way between their

side edges and extending from one cross reinforcement to the other cross reinforcement so that when the collar is folded it is 20 reenforced along the folded edge and so that when the buttonholes are made the material is reenforced around the buttonholes.

3. A collar comprising an outer section and an inner section, the end edges of the 25 two sections being folded inwardly and a reinforcement inserted between the folded edges and extending some distance from the folded edges to the inner side edges. 30

In testimony whereof I have signed my name to this specification.

THOS. B. WINNETT.
